LOCKING MECHANISM FOR BINDERS

Paul O. Unger, Chicago, Ill., assignor to Wilson-Jones Company, Chicago, Ill., a corporation of Massachusetts

Application June 15, 1931, Serial No. 544,323

8 Claims.

(Cl. 129—13)

This invention relates to locking mechanism for loose leaf binders. In certain types of loose leaf binders, the sides of the binder may be expanded or contracted through the use of telescopic posts. Springs are usually confined in certain posts and are designed for expanding or separating the two binder heads. Locking mechanism is usually provided in other posts for resisting the tendency of the springs to expand the binder.

10 This invention concerns itself more particularly with the locking means in certain of the telescopic posts for locking the binder heads in their adjusted position.

15 The invention comprises the novel structure and combination of parts hereinafter described and more particularly pointed out and defined in the appended claims.

20 In the accompanying drawings which illustrate a preferred form of this invention and in which similar reference numerals refer to similar features in the different views:

25 Figure 1 is a rear elevational view of a loose leaf binder involving this invention.

Figure 2 is a fragmentary plan view of such a binder.

30 Figure 3 is an interior fragmentary plan view of said binder.

Figure 4 is an enlarged sectional view taken upon the line IV—IV of Figure 2 looking in the direction of the arrows and showing some parts in elevation.

35 Figure 5 is an enlarged sectional view taken upon the line V—V of Figure 4, looking in the direction of the arrows and showing parts in elevation.

Figure 6 is an enlarged sectional view through one of the locking posts illustrated in Figure 4.

Figure 7 is a sectional view of a modified form of locking post that may be used.

40 Figure 8 is a view similar to Fig. 5 showing a modified form of locking post in the binder.

The loose leaf binder to which this invention is applied consists of a back portion 1 and a pair of clamping members 2 and 3 which are relatively

45 movable with respect to the back portion as is well-known in the art. Cover members 4 are hinged to the front edges of the clamping members 2 and 3 as is customary in the art. The two clamping members are connected by a pair of

50 telescopic posts 5 having coiled springs 7 in the interior thereof which normally tend to expand or separate the clamping members. These clamping members 2 and 3 are also connected by a pair of telescopic locking posts 6. In Figure

55 4, one post of each pair is shown in section. It

will be noted that the telescopic post 5 consists of an inner section having a head 5a secured to the clamping member 2 and the sleeve 5b that fits within the other post section which also has a head 5a thereon secured in the clamping member 3 and a sleeve 5c that telescopes over the sleeve 5b of the first section, with the result that the spring 7 which bears against the two heads of the post will normally tend to separate the heads.

Each locking post consists of a pair of telescopic sections provided with heads 6a secured to the different clamping heads of the binder. One head has an external sleeve portion 6b that telescopes over the interior sleeve portion 6c of the other section. Both of these locking posts are 10 similar in construction and a section upon an enlarged scale has been illustrated in Figure 6 to which reference may now be had. It will be noted that the interior sleeve section 6c has an upper 15 end bearing 8 secured therein and a lower sleeve bearing 9 secured therein. The lower sleeve bearing 9 is provided with a notch or opening having an upper sloping wall 10 and a lower horizontal wall 11.

The sleeve 6c is also provided with an opening in alignment with the opening in the sleeve member 9. A lock actuating rod 12 is slidably mounted in the sleeve bearings 8 and 9 and is provided with a collar 13 adjacent the bearing 8. A coil spring 14 surrounds the rod 12 and abuts the collar 13 and the upper end of the sleeve bearing 9. This spring 14 normally tends to urge the locking rod 12 upwardly.

A toggle locking plate member or element 15 which may be semi-circular or any desired shape is mounted in the opening in the bearing 9. The locking rod 12 is 20 provided with an aperture 16 terminating in an upper horizontal shoulder 17. It will also be noted that the sleeve member 9 is slightly recessed below the plate member 15 as indicated at 25 18 to provide proper clearance for the operation of the plate member 15. It will be noted that when the locking plate member 15 is in horizontal position, it engages the sleeve 6b and the wall of the recess 16 and frictionally binds the two telescopic post sections together. However, when 30 the rod 12 is pressed downwardly whereby the shoulder 17 will engage the plate member 15 and swing the same toward the inclined wall 10 of the opening, it will no longer lock the two sections together with the result that the springs 7 in the 35 posts 5 will automatically act to separate the two binder heads.

35 In referring to Figure 4, it will be observed that the two locking posts 6 are adjacent each other and the lock actuating or plunger rods 12 are 40

45

50

55

adapted to be simultaneously operated. To this end, the upper end of each plunger 12 is provided with a V-shaped notch 19 as shown more clearly in Figures 5 and 6 and a bar or bridging member 5 20 having V-shaped lugs 21 which fit in the notches 19 on the plungers for simultaneous operation. Mechanism has been provided whereby the bar 20 may be actuated externally of the binder. To this end a lever 22 (Figure 5) has been 10 provided and this lever is anchored in the upper wall of the clamping member 3 as indicated at 23 and extends over the plunger actuating bar 20 at which point it is deflected downwardly as indicated at 20a for engaging said bar. The lever 22 15 extends beyond the bar 20 a sufficient distance to provide proper leverage and its free end is in the form of a push button 24 which is normally pressed outwardly by means of a leaf spring 25 which is attached to the inner wall of the clamping member. The binder head 3 is provided with an aperture 26 as shown in Figure 2 just above the push button 24 of the lever 22 so that the finger of an operator may be inserted through the aperture 26 for depressing the lever 22 against 20 the tension of the spring 25 and through the instrumentality of the bar 20 depressing the plunger rods 12 for releasing the locking elements 15 as 25 previously explained so that the springs 7 in the posts 5 may separate the binder heads.

30 In Figure 7, a slightly different form of locking post has been illustrated that may be used in place of the post 6. This modified form of locking post consists of an outer sleeve section 27 and an inner sleeve section 28 which has an integral bearing at its upper portion. Below the upper bearing portion the sleeve member 28 is hollow and a sleeve member 29 is secured within the lower portion of the inner member a short distance above the lower end thereof. A plunger rod 30 extends through the bearing portions of the inner member and is provided with a collar 31 adjacent the upper integral bearing and a coiled spring 32 is confined between the collar 31 and the upper end of the bearing 29. Below the bearing 29, the member 28 is provided with diametrically opposite apertures 33 into which the ends of toggle levers 34 extend which are pivoted to the lower end of the plunger rod 30. In Figure 7 the plunger rod 30 is shown partially depressed in order to illustrate more clearly the action of the toggle levers 34. The spring 32 normally tends to force the plunger rod 30 upwardly for frictionally engaging the toggle levers 34 with the outer post section 27 for frictionally locking the outer and inner post sections together. It will be appreciated that when the collar 31 engages the upper shoulder of the hollow portion of the interior section the toggle levers 34 will be straightened and frictionally engage the exterior member 27. The toggle levers 45 extend through apertures in the inner section 28 and frictionally engage the outer section 27, so it will be obvious that they serve to frictionally lock the two post sections together.

50 In Fig. 8 there is illustrated the manner of incorporating the locking post shown in Fig. 7 in a binder. It is incorporated in the same way as the locking post shown in Fig. 6 except that it is necessary to bevel the slot in the screw head to receive the wedge portions 21 of the bridging element 20. It will be obvious that pressure exerted upon the bridging element 20 will simultaneously 55 actuate the two modified locking posts.

60 It will be appreciated that the different locking members act in the manner of toggles and effect a very quick and strong locking connection which.

however, requires but little effort to unlock. Moreover, the mechanism is very simple and readily manufactured and assembled in a manner that effectively retains the parts in assembled relation.

5

I am aware that many changes may be made and numerous details of construction may be varied through a wide range without departing from the principles of this invention, and I, therefore, do not purpose limiting the patent granted 10 hereon otherwise than necessitated by the prior art.

I claim as my invention:

1. A locking post for loose leaf binders comprising a pair of telescopic members, the inner member having an aperture communicating with the outer member, a spring pressed plunger rod slidably mounted in the inner member, the inner member and plunger rod having cooperating shoulders for limiting the outward movement of 20 said plunger and toggle locking mechanism controlled by said plunger rod for locking said members together.

2. A locking post for loose leaf binders comprising a pair of telescopic members, the inner member having upper and lower bearings and a space between said bearings, a plunger rod having a collar slidably mounted in said bearings, a spring located in said space between said collar and one of said bearings and a toggle lock for 30 frictionally locking said members together having connection with said plunger rod.

3. In a loose leaf binder, a pair of locking posts, each post comprising a pair of telescopic members, a toggle lock for frictionally locking each 35 pair of said members together, a plunger rod slidably mounted in each inner member and connected to its toggle lock, and means without the binder for simultaneously actuating said plunger rods.

4. In a loose leaf binder, a pair of locking posts, each comprising telescopic members, a toggle lock connecting the telescopic members of each post, a plunger rod extending through each inner member and connected to its toggle lock, and means including a lever actuated externally of the binder for simultaneously actuating said plunger rods for unlocking said toggle locks.

5. In a loose leaf binder, a pair of locking posts, each comprising telescopic members, a toggle lock 50 connecting the telescopic members of each post, a plunger rod extending through each inner member and connected to its toggle lock, a bridging member engaging the outer ends of said plunger rods and a lever for actuating said bridging member, said binder having an aperture for exposing said lever.

6. In a loose leaf binder, a locking post comprising an outer tubular member, an inner tubular member having an aperture communicating with the outer member, said inner member having upper and lower bearings, a plunger rod extending through said bearings, a collar upon said rod, a coil spring surrounding said rod between said collar and lower bearing and a frictional locking member between said rod and outer member and extending through said aperture and actuatable by said plunger rod for releasing its frictional engagement with the outer member.

7. In a loose leaf binder, a locking post comprising a pair of telescopic members, the inner member having upper and lower bearings, a plunger rod slidably mounted in said bearings, a collar upon said rod, a coil spring between said collar and lower bearing and a locking lever 75

adapted to increasingly exert pressure in a direction substantially normal to the direction of movement of the plunger rod, said locking lever being associated with said rod for frictionally engaging the outer member, said inner member having an aperture through which said lever extends.

8. In a loose leaf binder, a pair of locking posts, each comprising telescopic members, locking mechanism connecting the telescopic members

of each post, a plunger rod extending through the inner member of each post, and connected to the locking mechanism therein, a depressible bridging device extending over the outer ends of said plungers, and a lever engaging said bridging device for depressing the same and simultaneously depressing said plungers, said binder having an aperture through which said lever may be engaged.

PAUL O. UNGER. 10
